UNITED STATES PATENT OFFICE.

JOSEPH COHEN, OF TAUNTON, MASSACHUSETTS.

DESIGN FOR A CONTAINER FOR A VACUUM FLASK OR THE LIKE.

Application filed February 9, 1928. Serial No. 25,333. Term of patent 7 years

To all whom it may concern:

Be it known that I, JOSEPH COHEN, a citizen of the United States, residing at Taunton, in the county of Bristol and State of Massachusetts, have invented a new, original, and ornamental Design for a Container for a Vacuum Flask or the like, of which the following is a specification, reference being had to the accompanying drawing, forming part thereof.

The figure is a front elevational view of a container for a vacuum flask, showing my new design.

I claim:

The ornamental design for a container for a vacuum flask or the like, as shown.

JOSEPH COHEN.
